Pa., a corporation of New Jersey

Application October 27, 1944, Serial No. 560,606

12 Claims. (Cl. 200—51)

1

This invention relates to interconnectors and connector blocks of the type which permit a good electrically conductive, readily disconnectible interconnection to be made between two or more electrical conductors. The invention relates particularly to interconnectors and connector blocks for use with terminal connectors of the knife disconnect type, e. g. as described and claimed in my copending application, Serial No. 530,317, filed April 10, 1944.

It is frequently desirable in wiring systems to bring wires from various circuit elements to a convenient location where interconnections are made on a terminal block or panel. In this way installation, testing and replacement of circuits is facilitated. As a consequence of this practice there has grown up a demand for such interconnecting terminal blocks which are compact, well insulated against accidental contacts, which hold all connections securely and which are adaptable to various combinations of single and multiple connections and interconnections as required for various circuits. No interconnector is known to me other than that described herein, which fully satisfies this demand.

It is, therefore, an object of the present invention to provide an interconnector which is adapted for quick and ready connection and disconnection but in which connection is secure and constant when left in service. Another object is to provide an interconnector which is compact, occupying a minimum of space, but in which the connections are readily accessible. Another object is to provide an interconnector block in which all conducting parts are insulated from accidental contact while in normal use. Another object of the invention is to provide a standard interconnector block of relatively long lengths convenient for shipping and stocking from which convenient lengths with required number of connections can be cut at will and in which desired connectors can be electrically connected while others remain electrically isolated. Other objects and advantages will be apparent from the following specification and claims and the accompanying drawings.

Although in this specification and the accompanying drawings I am showing and describing a particular example and various modifications thereof, it should be understood that these are not intended to be exhaustive or limiting of the invention, but on the contrary are chosen and presented for purposes of illustration and in order to explain the principles of the invention and the practical employment of those principles in ap-

2

plying the invention to practical use, and thus to so fully instruct others skilled in this art that they will be enabled readily to modify and to select and substitute alternatives, each as may be best suited to the particular conditions of any given application or use.

In the drawings:

Figure 1 is a perspective view of an interconnector block with circuit wires leading into it and its cover locked in place as in normal use;

Figure 2 is a fragmentary plan view of one end of the block shown in Figure 1 with the cover removed, and the wire connections removed from one of the interconnector units;

Figure 3 is an end elevation of one of the interconnector units employed in the connector block;

Figure 4 shows a blank from which the integral interconnector shown in Figure 3 may be formed;

Figure 5 shows, partly in plan view and partly in longitudinal section, a modified interconnector unit suitable for use in a connector block such as that shown in Figures 1 and 2, but shown connected to two wires with a simple tubular insulating sheath;

Figure 6 shows, in plan view, a further modification of the interconnector unit;

Figure 7 is a view in side elevation of the interconnector of Figure 6;

Figure 8 is a fragmentary perspective view of one end of a connector block similar to that of Figure 1, but somewhat modified;

Figure 9 is a perspective view from the opposite side of the end fitting shown in Figure 8;

Figure 10 is a plan view of the blank from which the end fitting of Figure 9 is made; and

Figure 11 is a view in vertical section taken on line 11—11 of Figure 8.

In the embodiment of the invention shown in Figures 1 to 4, the connector block comprises a molded block of insulation 2, having therein transverse channels 4 each shaped to receive a novel two-way interconnector 5 of the present invention and having longitudinal channels 6 connecting successive transverse channels 4, these longitudinal channels 6 being adapted to receive, in overlapping relation, the integral contact lugs 7 extending laterally from the clips 10 of any two successive interconnectors 5.

The interconnector unit 5, as shown, is particularly designed for use with terminal connectors of the knife-disconnect type as sold commercially and more particularly described and claimed in my copending application, Serial No. 503,317,

filed April 10, 1944. This interconnector comprises two oppositely extending blade members 8 obliquely offset from each other so that they lie in spaced parallel planes. Integrally extending from the bottom of each blade at a distance from its end is a clip 10 adapted to receive the blade 12 of a knife-disconnect terminal connector, which on its part receives the blade 8 of the interconnector between its blade 12 and its clip 10.

The block 2 is formed with a cavity 15 in the bottom of each of diagonally opposite corners of each channel 4 under the freely extending blade portions 8. The depth of this cavity as well as the spacing of the blade portion 8 from the adjacent wall 13 is such as to facilitate positioning of the clip 10 under the blade when the terminal connector is pushed vertically to the bottom of the cavity 15 with lateral pressure against the wall 13. Thus the clip 10 is properly positioned; and when it is swung down into position parallel with the blade 8, the clip engages the blade as shown.

The wall 17 of the cavity serves as an abutment for the end of the terminal 12 to assure its assuming proper longitudinal relation to the blade 8 and the clip 10.

The two-way connector shown in Figures 1 to 3 can be formed from a single sheet metal stamping of which the flat blank outline is shown in Figure 4. Referring to this figure, it will be seen that the blank comprises the blade portions 8, a connecting saddle portion 16 and the clip parts 10 which are bent over the blades 8, to form the clips as shown in Figures 1 to 3. The oblique connecting body portion 16 is bent into U-shape to form a saddle portion, as shown in Figure 2. This automatically brings the blades 8 into parallel planes and into obliquely offset relation to each other. As also shown in Figure 3, the clip portions 10 are bent up into planes parallel to the planes of the blades 8, and spaced therefrom slightly less than the thickness of the blades.

As is evident from the drawings, both of the clips 10 open to the same side of the saddle portion 16 and thus, when assembled in the transverse channels 4 of the block, as shown in Figures 1 and 2, the blades 12 of the terminal connectors, after being inserted vertically, are engaged by being swung down parallel.

One of the practical advantages of the connector block of the present invention is that, when the conductor terminals having the counterparts of the knife switch elements constituting parts of the connector block have been cross connected and/or interconnected through the block and the cover has been placed in position on the block, all of the otherwise uninsulated conductive parts of the conductor terminals, two-way connectors, bridging switches, etc., are confined within the outer surfaces of the block, thus being protected from accidental contacts and short circuits. Only the insulated wire of the connections leading into the block is exposed beyond the insulation.

The invention further contemplates, in addition to the employment of the novel interconnector thus far described, a simple means for effecting interconnection and disconnection of successive interconnector units in the block to take care of circuits where more than two wires are required to be interconnected. To facilitate such interconnection there is formed, integral with each clip 10 of the two-way connector, a laterally extending contact lug 7. As shown in Figure 2, each contact lug 7 is formed by bending

the blank strip 7 first to a position at substantially right angles to the side wall of the clip 10 and then back upon itself with a slight outward bend at 26 to provide a concave recess in the free end of the contact of substantially arcuate curvature of the same or slightly smaller radius as the rotatable bridging contact member 28. The bridging member 28 is formed at least in part of metal adapted to conduct current between the contact lugs 7, it may be disconnected by being removed bodily, with or without substituting an insulating member as illustrated in Figure 11, or it may be disconnected by rotating to move the metal part 27 away from the contacts 7. In the latter case, the bridging member 28 may be made of insulating material with a metallic insert positioned and partially exposed so that in only one of the angular positions of the member 28 will the bridging connection be made between two adjacent overlapping contacts 7. The members 28 are rotatably mounted in bearings in the block 2 and are advantageously held in the bridging and insulating positions respectively by a spring detent, positioned for example on the ends of the members 28 in recesses at the bottom of block 2. The tops of members 28 are kerfed or otherwise provided with means for turning them to the connecting or disconnecting positions and for visually distinguishing said positions.

When the terminal connectors 12 are all in place as desired, the cover 30 is applied as shown and latched in place by spring clips 32 on the end fittings 34 engaging in grooves 36. When the cover is thus in place every conductive part is enclosed in the insulating block and moreover, since the terminal connectors 12 are fitted between the cover 30 and the bottoms of channels 4, they are held positively against release from engagement on the blades 8.

It will be observed also that the ends of the block 2 are like the corresponding parts of intermediate units, and that the entire block is made up of repetitive units each having the channels and recesses as described. Thus the device may be supplied in long strips and cut at any length. End fittings 34 slide onto the cut end of the block 2 and preferably an end plate 38 of insulation material is fitted over the end of the block 2 to assure complete insulation of the interconnectors 5 from the end fitting 34.

The end fitting 34 may be of any suitable form to engage the end of the block 2 and advantageously is provided with means for securing in place the cover 30. As shown, the end fitting is a sheet metal stamping formed with a bottom plate having a hole 40 for reception of a screw or other fastening to hold the assembly in place on a panel or other support, side channel portions 42 engaging ribs 44 on the bottom of the block 2 and thus securely holding block 2 when it is slid endwise into the fitting 34, and ears extending from the side portions 42, which are first turned inwardly at 46 to form end abutments limiting the entry of the block 2, and are then turned back into parallel position forming the ears 48 in which is mounted a pin 50 which constitutes an axle or pivot for the spring clip 32. The latter is provided near its end with a sharp fold forming a tongue 54 to engage in the slots 36 in the cover 30. With such standard end fittings supplied in quantity and the connector block with its contacts and interconnectors, as shown in Figure 2, supplied in conveniently long lengths, and the cover strip 30 likewise supplied in long lengths, the block and cover can be cut to any length desired to give the

proper number of connections; and, with two of the standard end fittings to be slipped over the ends of the block, a complete connector block, as shown in Figure 1, can be cut to size and assembled in a few minutes.

From the foregoing description it will be seen that the improved two-way connector of the present invention with its lateral contact extensions provides simple means not only for effecting interconnections through a connector block but for effecting interconnections between the two-way connectors within the block to obtain any desired multiple interconnections between conductors. It will be further seen that when the cross connections and interconnections have been made as shown in Figures 1 and 2, the terminal connectors 12 are overlapped so that the interconnections are made within a minimum width, only insulated parts of the interconnected conductors are exposed. Moreover, when the cover 30 has been put in position on the block 2, the terminal connectors are locked in the parallel position and thus are securely held against disengagement. There is thus no danger of accidental contacts being made which might cause current leakage or short circuits and no danger of accidental disconnection which could render any circuit inoperative.

Although the two-way interconnector unit 5 of Figures 1 to 4 is particularly designed to attain the objects and advantages stated in a connector block, it is to be understood that interconnector units of other design can be used within the scope of my invention and that certain inventions in the interconnector unit per se are useful and of advantage even apart from the other elements of the connector block. As illustration of this there is shown in Figure 5 a modification of the connector unit and it is shown as used apart from the connector block.

The interconnector shown in Figure 5 consists of a simple strip 5a of sheet metal having blade portions 8a lying respectively on spaced parallel planes with an offset portion 16a between, and an integral projection 10a from the bottom of each blade portion near the offset portion 16a. Each of these projections 10a is bent back over the face of its blade portion 8a but spaced therefrom a distance slightly less than its thickness. Thus the terminal connectors 12 are engaged by inserting their clips 14 under the blades 8a while blades 12 are perpendicular and then swinging the blades to the parallel positions, the bottoms 24a of clips 10a serving as fulcrums for pushing the clips 14 over the blades 8a and to limit the swinging of the terminals so as to assure the desired parallel positions and by engaging the clips 10a to prevent pulling apart of the terminals and interconnector by any pull on the wire. Thus it will be seen that the functioning and advantages of this form of interconnector are similar to those of the interconnector 5 of Figures 1 through 4.

The omission of the contact lugs 7 from the structure shown in Figure 5 and thus far described is optional—if the interconnector were to be used in the block 2 such lugs would advantageously be provided; whereas, as shown, the interconnector is used for connecting only two wires and instead of the fixed block 2 a simple tubular insulating sheath is shown at 2a; so that the lugs 7 are not only unnecessary but would be undesirable.

Since the interconnector as shown permits overlapping of the terminal connectors on the wire, the connection shown in Figure 5 is of par-

ticular advantage where space requirements limit the length of the terminal or the space available for swinging the wires in making connection and disconnection. Likewise, this may be used for connecting together terminals of different sizes. As shown in Figure 5, the lower right-hand connector portion has been reduced in thickness by the stamping operation and is otherwise dimensioned to interfit with the next smaller size of terminal connector than that which is engaged on the upper left-hand portion of the interconnector.

When the connection is made the insulating sheath 2a, which is advantageously a stiffly flexible tube of insulating material, for example a plasticized vinyl chloride, vinyl acetate copolymer, such as is available commercially under the trade name "Irvilite," is slipped over one wire. The connection is then made as described above and with the terminals 12 and 12a and the interconnector 5a in parallel relation, as shown, the tubular sheath 2a is slipped over the connection, which it engages snugly and elastically and is thus held securely in place at once, locking the connection against accidental disengagement, insulating it against accidental contact, and protecting it mechanically against accidental injury.

The use of an insulating housing for such a connection is not the present invention, but is more particularly described and broadly claimed in copending applications, Serial No. 558,328, filed October 12, 1944 and Serial No. 562,985, filed November 11, 1944. Likewise the knife disconnect principle used in the present invention is more particularly described and broadly claimed in copending applications, Serial Nos. 530,296 and 530,317, filed April 10, 1944.

The interconnectors shown in Figures 1 to 5, inclusive, are designed for use with terminal connectors of standard commercial design. If the design of the terminal connectors is modified, e. g. as shown at 12b in Figure 6, the design of the interconnector can be still further simplified, e. g. as in Figure 6, by omitting the offset 16a. In this case the interconnector is a simple straight strip so that the planes of its blade portions 8b are not only parallel but actually coinciding; and the only departure from a simple blade is the clip portions 10b bent up to opposite sides over the faces of the blades and at distances therefrom substantially equal to but slightly less than the thickness of the blades.

The interconnector as shown in Figures 6 and 7 may, as already mentioned in connection with Figure 5, be adapted to connect terminals of the same size or may connect terminals of different sizes. As shown, the interconnector is made with stock of thickness adapted to connect with the thinner of the two terminals and at the opposite end is punched to form a hump 60 and a corresponding recess on the other side such that a portion of the area engages the clip at its outside and the remaining area on its opposite side engages the blade. This arrangement also has the advantage of facilitating the entry of the blade under the clip, since the narrower stock readily enters between the clip and the blade of the counterpart connector and the border around the hump 60 serves as a ramp to cam the clip up over the hump area.

It is desirable in most cases to provide the clips 10, 10a, 10b, etc., but again this is not essential, especially where the terminals are held in proper alignment and pressed against blades 75 8a, etc., by external means, such as the sheath

2a. In all cases, however, it is advantageous to have some abutment means to serve as a fulcrum, to limit the swinging of the terminals and to resist separation by longitudinal pull. Some or all of these functions can be served by the offset 18 or 18a, by the bottom of the channel 4 or of the tube 2a or by lugs at the bottom of the blades corresponding the parts 24, etc. In the case illustrated in Figures 6 and 7, as in the case of Figure 5, the omission of lugs 7 is optional, depending upon the use to which the interconnector is to be put.

In Figures 8 to 11, inclusive, is shown a modified form of connector block similar to that of Figure 1. In this case, however, an end fitting is used which, as shown most clearly by Figure 10, can be stamped from a single piece of metal with full utilization. Portions 48a at the center are bent out on the lines indicated, the part 46a is then bent to vertical position, and side slide portions 42a are bent up first near the ends and then farther as indicated by broken lines on the drawing. The snap latch member 32a is then secured in place by bolt 50 and the end piece is complete.

As shown in Figure 11 the connection or insulation between the members 5 is made by bolts, 28a of brass where adjacent members 5 are to be connected, and 28a' having insulating sleeves 29. These bolts are secured in the block in any convenient manner; as shown, polygonal recesses are formed in the bottom of the block 2, which receive and fit nuts 35 into which bolts 28a and 28a' are threaded.

I claim:

1. A two-way interconnector of the knife disconnect type comprising oppositely extending but obliquely offset integrally connected blades and associated clips, said obliquely offset blades lying in parallel planes and the clips associated therewith opening to the same side of the connecting body portion of the interconnector.

2. A two-way interconnector according to claim 1 in which integral projections extend laterally from each clip, and a housing is provided for said interconnector with a chamber for said interconnector and recesses communicating with said chamber in which said projections are respectively received.

3. A two-way interconnector according to claim 1 in which the connecting body portion of the interconnector comprises a saddle strip arranged obliquely to integral parallel end portions and bent to bring the integral blades into parallel planes and to form the integral clips associated with the blades.

4. A terminal block which comprises an insulating block having transverse channels therein and communicating centrally located longitudinal channels, interconnectors in said transverse channels each having oppositely extending blade portions lying in spaced parallel planes, an integral centrally positioned saddle portion connecting and offsetting said blade portions and clip portions adjacent said saddle portion integrally connected to the blade portions respectively at the bottom edges thereof and extending over the face of the blade portion at a distance therefrom approximately the thickness of said blade portion and a contact lug extending laterally from each clip portion into said longitudinal channel in overlapping relation with the contact lug of an interconnector in an adjacent transverse channel, and a bridging connector removably engaged between said adjacent contact lugs.

5. whereby removably to connect said adjacent interconnectors, and an insulating cover closing said channels, insulating said interconnectors and locking said terminal connectors against disengagement from said interconnectors.

6. A terminal block as defined in claim 4 wherein end closures are fitted over the ends of the block and locking means on said end closures removably engage and hold said cover on said block.

7. A terminal block which comprises an insulating block having transverse channels therein and communicating centrally located longitudinal channels, interconnectors in said transverse channels each having oppositely extending blade portions lying in spaced parallel planes, an integral centrally positioned saddle portion connecting and offsetting said blade portions and clip portions adjacent said saddle portion integrally connected to the blade portions respectively at the bottom edges thereof and extending over the face of the blade portion at a distance therefrom approximately the thickness of said blade portion and a contact lug extending laterally from each clip portion into said longitudinal channel in overlapping relation with the contact lug of an interconnector in an adjacent transverse channel, and a bridging connector removably engaged between said adjacent contact lugs whereby removably to connect said adjacent interconnectors.

8. An interconnector which comprises oppositely extending blade portions lying in spaced parallel planes and an integral saddle portion extending between and offsetting said blade portions centrally of the interconnector, whereby the clip and blade of a knife disconnect type terminal may engage each of said blade portions while projecting portions of such terminal are accommodated by said offset, and clip portions adjacent said offset adapted to engage the edges of such knife disconnect type terminals to limit free swinging of such terminals and to serve as fulcrums for lifting clip portions of such terminals into engagement on said blade portions and to limit longitudinal movement of such terminals when subjected to axial pull, and each clip portion having a part thereof extending over a part of the blade portion adjacent the offset and spaced from said blade portion a distance approximately equal to its thickness, and an integral lug on each clip portion adapted for mounting the interconnector on a base.

9. An interconnector which comprises oppositely extending blade portions lying in spaced parallel planes and an integral offsetting portion extending between said blade portions centrally of the interconnector, whereby the clip and blade of a knife disconnect type terminal may engage each of said blade portions while projecting portions of such terminal are accommodated by said offset, clip portions adjacent said offset adapted to engage the edges of such knife disconnect type terminals to limit free swinging of such terminals and to serve as fulcrums for lifting clip portions of such terminals into engagement on said blade portions and to limit longitudinal movement of such terminals when subjected to axial pull, and each clip portion having a part thereof extending over a part of the blade portion adjacent the offset and spaced from said blade portion a distance approximately equal to its thickness.

10. A terminal block which comprises an insulating block having transverse channels therein, interconnectors in said transverse channels each having oppositely extending blade portions lying

in spaced parallel planes, an integral central portion connecting and offsetting said blade portions, clip portions adjacent said central portion integrally connected to the blade portions respectively at the bottom edges thereof and extending over the face of the blade portions at a distance therefrom approximately the thickness of said blade portions, and an insulating cover closing said channels and insulating said interconnectors and serving to lock terminal connectors against disengagement from said interconnectors.

10. A knife disconnect type interconnector which comprises a blank defining a pair of blades extending in opposite directions from a midpoint, each blade being adapted to be received between the blade and clip of a knife disconnect type terminal such as is engageable with the interconnector blade by a swinging-wiping action with respect thereto, each interconnector blade having an integral tab portion spaced back from its outermost end and bent out of the plane of the blade to form an abutment which limits swinging-wiping action of a terminal upon connection therewith, the tab portions of the two blades being spaced apart and being bent in opposite directions away from each other, a substantial portion of the edge of each blade between the respective tab portion and the outermost end of the blade lying closely adjacent the plane of the tab-formed abutment.

11. A knife disconnect type interconnector which comprises a blank defining a pair of blades extending in opposite directions in the same plane from a midpoint, each blade being adapted to be received between the blade and clip of a knife disconnect type terminal such as is engageable with

the interconnector blade by a swinging-wiping action with respect thereto, each interconnector blade having an integral tab portion spaced back from its outermost end and bent out of the plane of the blade to form an abutment which limits swinging-wiping action of a terminal upon connection therewith, the tab portions of the two blades being spaced apart and being bent in opposite directions away from each other, a substantial portion of the edge of each blade between the respective tab portion and the outermost end of the blade lying closely adjacent the plane of the tab-formed abutment.

12. A knife disconnect type interconnector as claimed in claim 11 wherein at least one of the blades is provided with a projection to produce a localized area of increased blade thickness and in which said projection is located between one of the tabs and the end of the blank.

JAMES C. MACY.
